UNITED STATES PATENT OFFICE.

EUGENE S. CRULL, OF MOUNT CARMEL, ILLINOIS.

TELEGRAPH-KEY.

SPECIFICATION forming part of Letters Patent No. 413,848, dated October 29, 1889.

Application filed March 21, 1889. Serial No. 304,106. (No model.)

To all whom it may concern:

Be it known that I, EUGENE S. CRULL, of Mount Carmel, in the county of Wabash and State of Illinois, have invented a new and Improved Telegraph-Key, of which the following is a specification, reference being had to the annexed drawings, forming a part thereof, in which—

Figure 1 is a side elevation of my improved telegraph-key. Fig. 2 is a vertical transverse section taken on line xx in Fig. 1. Fig. 3 is a plan view, and Fig. 4 is an inverted sectional plan view.

Similar letters of reference indicate corresponding parts in all the views.

The object of my invention is to construct a simple compact telegraph-key adapted to work on roller-bearings, thereby avoiding the rattle and sticking common to ordinary keys.

My invention consists in a key-lever provided with an annular bearing, the head or support having adjusting-screws for supporting and adjusting the balls of the ball-bearing of the key-lever.

It also consists in a double leg arranged to receive both wires.

The invention further consists in a circular contact-plate and an arm extending from the key and adapted to complete the circuit with the contact-plate when the key is depressed, all as will be hereinafter more fully described.

The head A, which forms the support of the key-lever B, consists of a base-plate a , provided with a hood b , extending upwardly from the base-plate, and having in opposite sides two threaded apertures c , in which are inserted the screws C. The adjoining ends of the screws C are grooved circumferentially to form bearings for the balls d.

The key-lever B is provided with an annular interiorly-grooved end e, which rides upon the balls d, which in turn roll in the grooves formed in the inner ends of the screws C. The adjustment of the bearing of the balls is secured by turning up one or both of the screws C.

The key-lever B is provided with an upwardly-extending arm f, which strikes the limit-screw g, inserted in an ear h, projecting upward from the hood b. The key-lever B extends downwardly, and is provided with an offset

arm i, which extends outward parallel with the plane of the base-plate a . It is also provided with an inwardly-turned arm j. The arm i is provided at its free end with a finger-piece k, and between the said finger-piece and the pivoted end of the lever is inserted an adjusting-screw l, which bears upon the retractile spring m, placed between the said screw l and the base-plate a . In apertures in the base-plate a is inserted the screw-threaded head n of the tubular leg o, the said leg being threaded throughout its entire length exteriorly. In the tubular leg o is inserted the inner leg p, which consists of a rod threaded at its lower end and insulated throughout its entire inclosed length. On the top of the leg p is placed a contact-disk r, and above the contact-disk r is arranged the circuit-closing key s, which, together with the said disk, is held in place upon the leg p by the screw t, inserted in the said leg, and the washer u, placed between the screw and the circuit-closing key. The said contact-disk r is insulated from the head n of the leg p by an insulating-washer v. On the lower end of the leg p is placed a nut w, between which and the lower end of the leg o is placed a washer a' of insulating material, and the said washer and nut are not threaded exteriorly, but are enough less in diameter to permit the passage of the wing-nut b'. Upon the outer leg o is placed the wing-nut b' and a washer c', and upon the leg p is placed a wing-nut d' and the washer e'. The base-plate a is provided with a contact f' for the circuit-closing lever s and an insulated pin to prevent lever s contacting with hood b when circuit-closing lever s is away from contact f'. The key is placed in the table by inserting the leg o in a hole bored in the table to receive it, and clamping the said leg by means of the wing-nut b', at the same time forming a contact with the conductor which is placed between the washer c' and the under surface of the table. The remaining conductor is inserted between the washer e' and the nut w, and is clamped by turning the wing-nut d'.

The key is used after opening the circuit and moving the circuit-closing key s away from the contact-key f' by depressing it in the usual way, thereby bringing the contact-arm j against the con-

tact-disk *r*, closing the circuit so that the current flows from the leg *o* through the base-plate *a* to the hood *b*, the screws *C*, the balls *d*, the key-lever *B*, the contact-arm *j*, the contact-disk *r*, and the inner leg *p*. By employing ball-bearings for the key *B* lateral motion and sticking or binding of bearings of the key is avoided and easy adjustment is provided by which the wear may be taken up 10 at any time.

Having thus described my invention, I claim as new and desire to secure by Letters Patent—

1. In a telegraph-key, the combination, with the key-lever *B*, provided with the annular internally-grooved end *e*, of the screws *C*, provided with grooved inner ends, the balls *d*, placed between the ends of the screws *C* and the annular ends *e* of the key-lever, and the supports and electrical connections, substantially as specified.

2. In a telegraph-key, the combination of the head *A*, provided with the apertured and internally-threaded base-plate *a*, the tubular

leg *o*, the inner leg *p*, the insulation separating the two legs, the contact-disk *r*, and the 25 circuit-closing lever *s*, placed upon the inner leg *p*, the key-lever *B*, provided with the contact-arm *f'* and the internally-grooved annular end *e*, the grooved screws *C*, and the balls *d*, substantially as specified. 30

3. In a telegraph-key, the combination of the head *A*, provided with the apertured and internally-threaded base-plate *a*, the tubular leg *o*, the inner leg *p*, the insulation separating the two legs, the contact-disk *r* and the 35 circuit-closing lever *s*, placed upon the inner leg *p*, the key-lever *B*, provided with the contact-arm *f'* and the internally-grooved annular end *e*, the grooved screws *C*, the balls *d*, the limit-screw *g*, and the retractile spring *m*, 40 substantially as specified.

EUGENE S. CRULL.
